UNITED STATES PATENT OFFICE

107,901

DESIGN FOR AN AIR CONDITIONING CASING

Charles A. Arnold, Cranston, and Eric P. Hanson, Providence, R. I., assignors to General Fire Extinguisher Company, Providence, R. I., a corporation of Delaware

Application November 26, 1937, Serial No. 73,194

Term of patent 14 years

To all whom it may concern:

Be it known that we, Charles A. Arnold and Eric P. Hanson, citizens of the United States, residing respectively at Cranston and Providence, both in the county of Providence and State of Rhode Island, have invented a new, original, and ornamental Design for an Air Conditioning Casing, for which the following is a specification, reference being had to the accompanying drawing, forming part thereof.

Figure 1 is a front perspective view of an air conditioning casing, showing our new design; and Figures 2, 3 and 4 are front and side elevations and a plan, respectively, of the same.

We claim:

The ornamental design for an air conditioning casing as shown.

CHARLES A. ARNOLD.
ERIC P. HANSON.
